UNITED STATES PATENT OFFICE.

WILLIAM C. SPONHOLZ, OF CHICAGO, ILLINOIS, ASSIGNEE TO INTERNATIONAL SILVER COMPANY, OF BRIDGEPORT, CONNECTICUT, A CORPORATION OF NEW JERSEY.

DESIGN FOR A SPOON OR SIMILAR ARTICLE.

Application filed March 9, 1929. Serial No. 30,395. Term of patent 7 years.

To all whom it may concern:

Be it known that I, WILLIAM C. SPONHOLZ, a citizen of the United States, residing at Chicago, county of Cook, State of Illinois, have invented a new, original, and ornamental Design for a Spoon or Similar Article, of which the following is a specification, reference being had to the accompanying drawings, forming part thereof.

Fig. 1 is a face view of a spoon showing my new design,

Fig. 2 is a fragmentary showing of the reverse of the spoon shown in Fig. 1, and

Fig. 3 is a sectional view on the line 3—3 of Fig. 2.

I claim:

The ornamental design for a spoon or similar article substantially as shown.

WILLIAM C. SPONHOLZ.
